UNITED STATES PATENT OFFICE.

ELROY ALBERT CHASE, OF NORTHFIELD, VERMONT.

COARSE-GRINDING WHEEL.

Application filed May 24, 1922. Serial No. 563,413.

To all whom it may concern:

Be it known that I, ELROY A. CHASE, a citizen of the United States, residing at Northfield, in the county of Washington and State of Vermont, have invented a new and useful Coarse-Grinding Wheel, of which the following is a specification.

This invention relates to a wheel for use in grinding stone and particularly for performing the so-called "coarse-grinding" operation upon blocks of granite.

It is the object of my invention to provide a wheel for such purposes possessing special features of construction by which the rate of production of finished surface is very materially increased.

A particular feature of my invention consists in the provision of pockets in the inner and lower faces of the rings which engage the work, these pockets being of a peculiar shape particularly adapted for storing abrasive material and for feeding the same under the grinding surface of the wheel.

My invention further relates to arrangements and combinations of parts which will be hereinafter described and more particularly pointed out in the appended claims.

A preferred form of the invention is shown in the drawings, in which

Fig. 1 is a top plan view of my improved grinding wheel;

Fig. 2 is a side elevation thereof, partly in section;

Fig. 3 is a detail bottom view looking in the direction of the arrow 3 in Fig. 2; and

Fig. 4 is a detail side elevation of a portion of one of the rings, looking in the direction of the arrow 4 in Fig. 3.

Referring to the drawings, I have shown a grinding wheel preferably comprising two separable castings. One of these castings forms a grinding head 10 having projecting flanges or arms 11 secured by bolts 12 to the lower portion or grinding member of the wheel. A central opening 13 is formed in the head 10 by a vertically extending flange or ring, and a driving member 14 is connected to said ring by a plurality of inclined arms 15.

These arms 15 serve not only for transmitting the driving force from the member 14 to the grinding wheel but also have a propeller-like action in feeding the abrasive downward through the central opening to the working surface. It is thus possible to feed

the abrasive continuously and, if desired, automatically while the wheel is rotating at relatively high speed.

The working portion of the wheel comprises a series of preferably concentric rings 16 formed integral with a plurality of radially disposed arms 17. Certain of these arms as 17^a are of increased thickness and are provided with seats or bearing surfaces for the arms or flanges 11 of the driving head. An annular connecting portion 18 may also be provided for stiffening and strengthening the wheel. The arms 17 are preferably equally spaced so that the wheel is of equal stiffness or rigidity in all directions.

In the preferred form of manufacture, the entire working portion of the wheel including the rings 16 and radiating arms 17 is formed as a single unitary casting, commonly of cast iron, while the driving head 10 is similarly formed as a second unitary casting. As these wheels are made of large diameter and rotate at high speed, it is sometimes desirable to provide a band 19 of steel or wrought iron encircling the grinding member and reducing the possibility of accident from breakage thereof.

A very important feature of my invention consists in the provision of a series of pockets 20 in the inner and lower faces of each ring 16. These pockets, as shown in Figs. 3 and 4 are inclined upwardly and forwardly in the direction of rotation and are open on their inner sides and bottom faces. The pockets are also preferably enlarged slightly in cross section toward their open ends to facilitate the delivery of abrasive therefrom.

These grinding wheels wear away rapidly on their working faces and it will be evident that a pocket formed as disclosed in Fig. 4 will present an outlet in the working face which is maintained of substantially constant size as this lower surface is ground away. In this way the amount of grinding surface is maintained substantially constant during the life of the wheel. When the wheel becomes too thin for further use, the lower casting or grinding portion thereof is removed and a new grinding member substituted therefor.

The pockets 20 are found to have a very important function in increasing the capacity of the grinding wheel. As the abrasive fed through the central opening 13 is moved outward by centrifugal force, it enters

through the side openings of the pockets and is stored therein, while at the same time it works gradually downward for delivery to the work directly under the inclined rear edge of the pocket and in the path of the advancing grinding surface of the ring. Furthermore, the storage action of the pockets is sufficient to permit the use of the wheel upon blocks of less diameter than the wheel, as the pockets in a portion of the wheel leaving the work retain the abrasive so that this portion of the wheel immediately resumes its grinding operation as soon as it again engages the stone. With the plain ring wheels previously used, such results did not obtain, as the abrasive was merely swept off the edge of the stone whenever a portion of the wheel passed beyond the edge thereof.

Having thus described my invention and the advantages thereof, it will be evident that changes and modifications can be made therein by those skilled in the art within the spirit and scope of my invention as set forth in the claims, and I do not wish to be other-

wise limited to the details herein disclosed but what I claim is:—

1. A coarse grinding wheel comprising a plurality of concentric rings each having a series of pockets in its inner side and bottom face, said pockets being inclined upwardly and forwardly and each having a substantially constant area of delivery opening throughout its length in the plane of the grinding surface.

2. A coarse grinding wheel comprising a driving head having a central feed opening, and a plurality of rings and integral radiating arms formed as a separate unit detachably secured to said head and driven thereby, said rings having pockets in their inner sides and bottom faces to receive and store abrasive as the wheel is rotated and said arms being closely adjacent and equally spaced.

In testimony whereof I have hereunto affixed my signature.

ELROY ALBERT CHASE.
